C. H. TAYLOR,
DISAPPEARING BED,
APPLICATION FILED AUG. 7, 1915.

1,239,540.

Patented Sept. 11, 1917.

UNITED STATES PATENT OFFICE.

CHARLES H. TAYLOR, OF SOUTH ORANGE, NEW JERSEY.

DISAPPEARING BED.

1,239,540.

Specification of Letters Patent. Patented Sept. 11, 1917.

Application filed August 7, 1915. Serial No. 44,147.

To all whom it may concern:

Be it known that I, CHARLES H. TAYLOR, a citizen of the United States, and resident of South Orange, in the county of Essex and 5 State of New Jersey, have invented certain new and useful Improvements in Disappearing Beds, of which the following is a specification.

My invention has for its object to provide 10 an improved disappearing bed construction for use in dwellings in which it is desired to economize space. This object I attain by means of the novel construction, arrangement and combinations of parts hereinafter 15 described in connection with the accompanying drawings and more particularly pointed out in the appended claim.

In the accompanying drawings,—

Figure 1 is a vertical section taken on the 20 line 1—1 of Fig. 2, showing a section of a building provided with a bed construction embodying my invention, the bed being shown by dotted lines in its closed vertical position within a recess formed in one of 25 the side walls of a room, and by full lines swung down to its open horizontal position projecting out of said recess into the room.

Fig. 2 is a view of the bed in its closed 30 vertical position, looking from the right as viewed in Fig. 1.

In these drawings, my invention is shown as embodied in the permanent structure of a building, although it may also be embodied in a self-contained article of furniture as 35 will hereinafter appear.

The building structure here shown is a section of a bungalow, in which type of dwelling it is particularly desirable to economize space. The section of structure 40 shown comprises the floor 1 spaced from the ground by a supporting foundation 2, and an extension 3 built out from the side 4 of the building; this extension being made to provide a recess 5 in the side wall of the 45 room in which a bed may be located when not in use and from which the bed may conveniently be moved out into the room when desired for use.

In accordance with my invention, the bed 50 is adapted to be pivotally supported for swinging movement to and from its position within the recess 5. The bed employed may be of any suitable construction, but usually I employ an ordinary spring bed comprising 55 the usual metallic frame 6 and attached spring 7. Suitably secured to the under side

of this bed adjacent one end thereof, as by means of sleeves 8, 8, attached to the bed, is a transversely arranged rod 9 which projects at its ends beyond the opposite sides of 60 the bed to provide trunnions 10, 10, for the pivotal support of the bed in the manner referred to, these trunnions being seated in open bearings 11 formed in the upper ends of vertical supports 12, 12, at the opposite 65 sides of the recess 5, as shown. When the bed is turned down to open position, it is supported at its inner end by these trunnion supports and at its opposite or outer end is supported by an attached bracket 13, which 70 as here shown, is adapted to provide a horizontally arranged shelf when the bed is turned up to its closed position. Any suitable support for the outer end of the bed may, however, be employed in lieu of this 75 bracket shelf.

As the axis about which the bed turns in swinging on its trunnions is at some considerable distance from the center thereof, it is necessary, in order to permit of the easy 80 and convenient swinging of the bed to and from its closed position, to provide counterbalancing means for the same. This may be done in any desired way. As here shown, I attach a box-like container 14 to the under 85 side of the bed at the short end thereof as measured from its axis, which container is preferably formed with two compartments. In one indicated at 15 is located a heavy 90 material 16, such as concrete, to serve as a counterbalancing means for the bed. The second compartment of the container, indicated at 17 is adapted for use as a receptacle for articles of any kind and is closed by a movable lid 18 which, when the bed is swung 95 upwardly to its vertical closed position, is adapted to present a horizontal seat, as most clearly shown by dotted lines in Fig. 1.

In addition to the container 14, I also provide in some instances a second container 19 100 having a removable cover 20, into which additional counterbalancing material may be conveniently placed in such quantities as may be necessary to regulate the counterbalance of the bed with some substantial 105 degree of accuracy. This second container 19 is preferably located at the upper side of the bed in a position to serve as a foot-board for the same as shown.

The bedding, indicated at 21, may be held 110 to the bed when swung upwardly to its closed position, by any suitable means. As

here shown, I provide a head-board 22 having a hinged section 23 which may be turned downward into holding position over the adjacent end of the bedding and be secured in such position by a suitable hook device 24, as indicated by dotted lines in Fig. 1. This forms a simple and effective means for the purpose indicated.

In order that the bed may be adjusted depthwise of the recess 5 and also vertically thereof, I have provided a series of obliquely arranged trunnion bearings 11 at the upper ends of the vertical supports 12, from one to the other of which the trunnions on the bed may be readily shifted to obtain the desired adjustment.

In order that the bed when in its closed vertical position may present an attractive appearance at its exposed side—which is the under side of the bed when in use—it is preferably provided at such side with a suitably attached covering piece 25, here shown in the form of a looking glass.

In the use of folding or disappearing bed as usually provided, more or less serious objection is made because of the lack of proper ventilation of the bedding. In accordance with my invention I overcome this objection by providing for a circulation of air through the compartment or recess 5 in a path adjacent the bedding on the bed. This I provide by locating openings in the floor and wall of the recess 5, as indicated at 26 and

27 respectively, through which the air passes or circulates in a path as indicated by the arrows in Fig. 1. These openings are preferably covered by a fine wire gauze as shown.

As hereinbefore stated, my invention may be embodied in a self-contained article of furniture equally well as in the permanent structure of a building as illustrated. For instance, the invention may be embodied in a movable wardrobe substantially corresponding to the building extension 3 as to the features of bed support and air circulation, and for such reason I have used the term "compartment" in the claim to include a recess for the bed whether formed in a stationary or movable receptacle.

What I claim is:

The combination with a building including a recess forming extension having air openings in the floor and a wall thereof, of a bed pivotally mounted in the recess for movement into horizontal and vertical positions, the pivot of the bed being adjustable into the recess to various degrees whereby the head of the bed may be extended into the recess to various degrees.

Signed at New York, in the county of New York, and State of New York, this 30th day of July, A. D. 1915.

CHARLES H. TAYLOR.
